United States Patent Office

Des. 208,522
Patented Sept. 5, 1967

208,522

TWO-PORT CONNECTOR BLOCK

Charles H. Graham, Mountain View, Calif., assignor to

Gra-Tec, Inc., Los Altos, Calif.
Filed Oct. 24, 1966, Ser. No. 4,385

Term of patent 14 years

(Cl. D91—3)

FIG.1

FIG.2

FIG.4

FIG.3

FIGURE 1 is a perspective view of the connector block embodying my design;

FIGURE 2 is a plan view of the two-port connector block shown in FIGURE 1;

FIGURE 3 is a front elevational view of the connector block shown in FIGURE 1, the back being a mirror image thereof; and

FIGURE 4 is a side elevational view of the connector block shown in FIGURE 1, the reverse side being a mirror image thereof.

I claim:

The ornamental design for a two-port connector block, as shown and described.
